S. H. SIMPSON,
MEMORANDUM BOOK,
FILED OCT. 31, 1921.

Inventor

Stanley H. Simpson
By William Bradbury
McClint & Rice
Attorneys

UNITED STATES PATENT OFFICE.

STANLEY H. SIMPSON, OF WINNETKA, ILLINOIS.

MEMORANDUM BOOK.

Application filed October 31, 1921. Serial No. 511,639.

To all whom it may concern:

Be it known that I, STANLEY H. SIMPSON, a citizen of the United States, and resident of Winnetka, in the county of Cook and State of Illinois, have invented a certain new and useful Improvement in Memorandum Books, of which the following is a full, clear, concise, and exact description, reference being had to the accompanying drawings, forming a part of this specification.

My invention contemplates the provision of a memorandum book consisting of an improved pad and a novel cover in which the pad is inserted.

The memorandum book, as a whole, is extremely durable in construction and is designed to present a pleasing appearance. Both the insert and the cover may be economically manufactured. The pad and cover are so constructed and arranged that the former is held firmly, but removably, within the latter by reason of the engagement of the ends of the pad back with a certain pocket and retaining strip with which the cover is provided. One feature of the present invention is the fact that the aforesaid pocket is provided with a window formed by removing from the inner wall of the pocket a portion of the material thereof, which is utilized as the retaining strip.

Other features of my memorandum book will appear as the following detailed description progresses. In the accompanying drawings illustrating my invention:

Figure 1 is a view in perspective of the device of my invention, the cover being illustrated in open position;

Figure 2 is a longitudinal section, the cover being illustrated in closed position;

Figure 3 is an inside view of the cover in open position, the insert being removed;

Figure 4 illustrates the piece of leather from which the body portion of the cover is formed; and

Figure 5 illustrates a leather blank from which the apertured pocket strip and the retaining strip of the cover are formed.

Similar characters of reference refer to similar parts throughout the several views.

Referring to the drawings, the cover is indicated as a whole at A and the pad is indicated as a whole at B. The cover comprises as its body portion a strip 10 of leather or other similar material, to one end 55 of the inner surface of which is attached a

pocket strip 11, which is likewise formed of leather or other similar material. Three edges of the pocket strip are firmly attached to the body strip 10 by stitching 12, which is preferably carried entirely around the body strip in lines parallel with the edges thereof. The stitching 12 likewise firmly attaches the lateral edges of the retaining strip 13 to the body strip 10.

In Figure 4 I have illustrated the body strip 10 as it appears before strips 11 and 13 and stitching 12 have been applied. In Figure 5 I have illustrated a leather blank from which the pocket strip 11 and the retaining strip 13 are formed. It will be noted that the blank has the same dimensions as the pocket strip 11, illustrated in Figure 3. It will be noted that the dotted lines 14 in Figure 5 circumscribe a portion of the blank which corresponds in its dimensions with the retaining strip 13 of Figure 2. The blank is cut along lines 14 and that portion of the blank which was circumscribed by lines 14—14 is utilized as the retaining strip 13, the outer or marginal portion of the blank being utilized as the pocket strip 11.

Now let us refer to the insert B. This insert comprises a plurality of sheets constituting a pad 15 which is attached by staples 16—16 to the light cardboard insert back-strip 17. The back-strip 17 is of substantially the same width as the pad 15, but the length of the strip 17 is substantially twice that of the pad. The staples 16—16 engage strip 17 at points substantially intermediate its ends. If desired, the several sheets of pad 15 are scored, as indicated at 18, to facilitate their detachment from the pad.

In applying the insert to the cover, that end of back-strip 17 which lies behind the pad is slipped under retaining strip 13 and the other end of strip 17 is slipped into the pocket afforded by strip 11. The insert is thus held firmly but removably in the cover, the insert back-strip being free to fold with the cover and to move slightly with respect to the cover under flexure to prevent buckling.

I may state at this point that the inner face of that part of the back-strip which lies in the pocket may be provided with calendar indicia or the like, which is visible through the pocket window. If desired, a sheet of celluloid 19 may be slipped into the pocket, as illustrated. The celluloid prefer-

ably fits snugly within the pocket and requires no stitching, adhesive or the like to hold it in position.

Having thus described my invention, what I claim is new and desire to secure by Letters Patent of the United States is:

1. In a memorandum book, a body strip adapted to be folded along its transverse centre, a pocket strip applied to the inner 10 surface of an end of said body strip and having its lateral edges and one end stitched to the sides and the outer end of said body strip, a substantially rectangular portion cut from the centre of said pocket strip to form 15 an opening in said pocket strip, a pad retaining strip formed of the rectangular portion cut from the pocket strip and attached across the inner surface of the body strip near but not at the end opposite that to 20 which the pocket strip is attached, a pad, said pad being attached to a back strip substantially twice as long as said pad and adapted to be approximately at its transverse centre, one end of said back strip being 25 removably inserted in said pocket strip and provided with inscriptions visible through the rectangular opening thereof, and the other end being removably inserted through the retaining strip.

2. The method of manufacturing a memorandum book which comprises making a cover therefor by attaching a pocket strip at one end of the inner surface of a body strip adapted to be folded at its approximate centre, cutting a substantially rectangular portion from the pocket strip to form an opening in said pocket strip, attaching said rectangular portion across the inner surface of the body strip near but not at the end opposite that to which the pocket strip is attached to form a retaining strip, providing a pad having a back strip of substantially twice the length of the pad, said back strip having approximately one half its length in contact with the pad and adapted to fold at the centre, removably inserting an end of said back strip in said pocket strip and the other end through said pad retaining strip, inscriptions being provided on the inner surface of the end of said back strip, and said inscriptions being visible through the rectangular opening of said pocket strip.

In witness whereof, I hereunto subscribe my name this 28th day of October, 1921.

STANLEY H. SIMPSON.
